SEISMOGRAPHIC PROSPECTING

Alfred C. Winterhalter, Beaumont, Tex., assignor
to Sun Oil Company, Philadelphia, Pa., a corporation of New Jersey

Application August 3, 1939, Serial No. 288,156

5 Claims. (Cl. 177—352)

This invention relates to seismographic prospecting, and particularly to improved means for recording the instant an explosion takes place.

In seismographic work it is essential that the instant of explosion be determined on the record to a high degree of accuracy, and it is customary, therefore, to record the instant at which the firing circuit is disrupted by the explosion. Difficulties are sometimes encountered, particularly when the instant of break is transmitted by radio to a remote recording station in securing a sharp indication of the instant when the break occurred. Usually both the make and break of the firing circuit are noted, and in the event that the break is not sharply indicated, the time of break may be determined with more or less accuracy from the less significant instant when the circuit is made, using the knowledge of the approximate delay between the make of the circuit and the break occasioned by the explosion.

In accordance with the present invention, the break only is recorded, without any interference due to the making of the firing circuit. A sharp indication of the instant of break may thus be transmitted either by wire or by radio to the recording apparatus. Specifically, in accordance with the invention, the break is used to produce a voltage adapted to fire a gas filled tube to produce an impulse arranged to control the operation of a radio transmitter.

The broad and subsidiary objects of the invention will become apparent from the following description, read in conjunction with the accompanying drawing, in which:

Figure 1 is a wiring diagram showing the improved circuit applied to firing by means of a blasting machine; and

Figure 2 is a partial similar diagram illustrating the modifications necessary in the event that firing is accomplished by the use of a battery.

Referring first to Figure 1, there is illustrated at 2 a triode, which may be interposed between the oscillator 4 and the amplifier 6 of a conventional radio transmitting circuit, or which may be one of the amplifying tubes of the amplifier system. The amplifier, in any event, feeds the transmitting antenna 8 from which a signal is sent to a remote recording apparatus. A leak circuit of the grid 10 of the tube 2 comprises a radio frequency choke 12 and series resistances 14 and 16, the two resistances together forming the proper grid leak for normal operation and the resistance 16 being of proper value for controlling the gas tube circuit, as hereinafter described.

At 18 there is indicated a gas triode of the cold- 55

cathode starter-anode type. This tube may, for example, be of the OA4-G type and may comprise the anode 20, cathode 24 and starter-anode 26. The operation of this type of tube is well known and involves the initiation of a discharge between the cathode and starter-anode, which discharge effects a discharge between the cathode and anode if the anode potential is sufficiently high and the starter-anode current exceeds some predetermined value. For example, in a typical case, 90 volts between the starter-anode and cathode will produce a discharge between them. If, then, the anode voltage with respect to cathode is about 180 volts, a current of 25 microamperes in the starter-anode circuit will cause a discharge between the cathode and anode. On the other hand, if breakdown of the starter-anode circuit has not occurred, the anode breakdown will not occur until a minimum potential of about 225 volts between the anode and cathode is exceeded.

Connected to the junction point of the resistances 14 and 16 is a battery 22 having a voltage of, for example, 180 volts. A switch 23 is interposed between the positive side of this battery and the anode 20, this switch serving to interrupt the discharge at a proper time.

The cathode 24 may be connected directly to ground and the cathode of the tube 2.

The starter-anode 26 is connected through a current limiting resistance 28 to the positive pole of the blasting machine, indicated at 32. Shunted across the blasting machine are the stabilizing resistance 30, which may have a high value such as one megohm, a safety switch 38, which is closed except at the time of firing, and the leads 34 connected to the igniting filament 36 of the detonator of the charge 37. The leads 34 should be well insulated to prevent leakage and maintain high the resistance across the blasting machine upon breaking of the igniting filament.

In the operation of this arrangement, following the proper placing of the charge and the rendering of the radio transmitter operative to transmit a continuous wave, the safety switch 38 is opened to remove the short circuit from the firing leads and the switch 23 is closed to impose the potential of the battery 22 upon the anode. The potential thus imposed is insufficient to cause discharge in the absence of discharge at the starter-anode, and consequently no current flows through the resistance 16 except the normal grid current of proper amount to provide the bias for the amplifying tube 2.

When the blasting machine 32 is operated, its

terminal voltage is impressed upon the starter-anode and the leads to the filament 36. The filament 36, however, is of low resistance and the internal impedance of the blasting machine is sufficiently high so that accompanying the relatively heavy current which flows to the igniting filament there is a terminal voltage considerably less than the 90 volts required to initiate starter-anode discharge.

At the instant the filament is disrupted by the explosion, however, the terminal voltage of the blasting machine rises instantly to its open circuit value, the high resistance 30 offering no substantial load. This open circuit potential is generally about 150 volts, quite sufficient to initiate the starter-anode discharge. Furthermore, the voltage is sufficiently high to cause to flow through the starter anode and its series resistance 28 a current of sufficient value to initiate anode discharge under the 180 volts provided by the battery 22. As soon as discharge is initiated, the potential drop between the anode and cathode reaches a value substantially constant at 70 volts, and hence the difference voltage between the voltage of the battery and this potential drop is imposed across the resistance 16, biasing the tube 2 to cut-off. Since there is no large impedance in the circuit capable of producing any appreciable delay, it will be evident that for all practical purposes the cut-off of the tube 2 occurs at the instant of the firing of the shot. Thus this instant may be transmitted to secure a record of extremely high accuracy.

The switch 23 to interrupt the anode discharge may be connected to the send-receive switch of the radio. The value of the resistance 16 must be such as to limit the anode current to a safe value to prevent damage to the tube 18. The resistance 28 likewise prevents damage which might be caused by excessive starter-anode current. The leak resistor 30 must be provided to avoid accidental tube discharges which may occur in the event that the starter-anode is "free."

While a cold cathode gas tube has been specifically described, it will be evident that hot cathode types may be equally well used. The grid or starter-anode control may be either positive or negative, depending upon the type of tube, suitable biasing being provided if necessary. In general, gas rather than vapor tubes are to be recommended because of the possible instability and accidental discharge of vapor types.

In Figure 2 there is illustrated the modification necessary to adapt the circuit to battery firing. The tube 18 may be of the same type as that of Figure 1, for example an OA4-G. The firing battery is indicated at 40, while at 42 there is indicated the internal resistance of the battery or, in the event that that is insufficient, an auxiliary resistance adapted to insure that, when the circuit is closed for firing by means of the switch 43, the terminal voltage is insufficient to cause a starter-anode discharge. In case a battery is used, the voltage necessary to produce starter-anode discharge would be considerably in excess of the voltage desired for firing the detonator. Accordingly, a bias battery 44 is introduced adapted to maintain on the starter-anode a voltage insufficient to cause its discharge upon closure of the firing circuit, but sufficient to produce discharge when added to

the open circuit voltage of the battery 40, which is imposed across the resistance 30 as soon as the filament is disrupted by the explosion. In all respects except those noted, the circuit is, of course, the same as that of Figure 1.

What I claim and desire to protect by Letters Patent is:

1. In combination, a firing circuit for an explosive charge, current supplying means for said circuit, signal transmitting means, and means for controlling the transmitting means to transmit a signal upon disruption of the firing circuit by explosion of a charge, said last named means comprising a grid controlled electronic tube of relay type having its grid input circuit connected across said current supplying means in shunt with said firing circuit so that upon disruption of the firing circuit the potential of the grid is raised sufficiently to cause discharge of said tube.

2. In combination, a firing circuit for an explosive charge, current supplying means for said circuit, signal transmitting means, and means for controlling the transmitting means to transmit a signal upon disruption of the firing circuit by explosion of a charge, said last named means comprising a grid controlled electronic tube of relay type having its grid connected to said firing circuit in a manner to render it operative upon disruption of the firing circuit.

3. In combination, a firing circuit for an explosive charge, current supplying means for said circuit, signal transmitting means, means for controlling the transmitting means to transmit a signal upon disruption of the firing circuit by explosion of a charge which simultaneously causes an electrical change in the firing circuit, said last named means comprising a grid controlled electronic tube of relay type arranged to discharge by rise of grid potential, and connections between the tube and firing circuit whereby said electrical change effects a rise of grid potential to the discharge point upon disruption of the firing circuit.

4. In combination, a firing circuit for an explosive charge, current supplying means for said circuit, signal transmitting means, means for controlling the transmitting means to transmit a signal upon disruption of the firing circuit by explosion of a charge which simultaneously causes an increase of voltage across the firing circuit, said last named means comprising an electronic tube of relay type, and connections between the tube and the firing circuit whereby it is arranged to discharge in response to said increase of voltage across the firing circuit upon disruption thereof.

5. In combination, a firing circuit for an explosive charge, current supplying means for said circuit, signal transmitting means comprising a thermionic vacuum tube having a grid, and means for controlling the transmitting means to transmit a signal upon disruption of the firing circuit by explosion of a charge which simultaneously causes an electrical change in the firing circuit, said last named means comprising an electronic tube of relay type, and connections between the last mentioned tube and the firing circuit whereby it is arranged to discharge upon the disruption of the firing circuit, and connections through which such discharge changes the bias on said grid.

ALFRED C. WINTERHALTER.
